SELECTIVE DEMETHYLATION OF SATURATED HYDROCARBONS

Vladimir Haensel, Clarendon Hills, and Vladimir N. Ipatieff, Chicago, Ill., assignors to Universal Oil Products Company, Chicago, Ill., a corporation of Delaware

No Drawing. Application December 29, 1945,
Serial No. 638,482

10 Claims. (Cl. 260—683.6)

1

This invention relates to the treatment with hydrogen in the presence of a hydrogenating catalyst of a saturated hydrocarbon to produce therefrom another saturated hydrocarbon containing at least 1 carbon atom less than those present in the hydrocarbon charged to the process. More specifically, our invention is concerned with a catalytic process for treating with hydrogen a saturated hydrocarbon containing more than four carbon atoms including an alkyl group of at least 2 carbon atoms, said process being carried out at closely correlated conditions of temperature, hydrogen partial pressure and charging rate so that the principal reaction of the process is the replacement with hydrogen and the scission of methyl groups, in the form of methane, to the exclusion of alkyl groups of more than 1 carbon atom, to decrease the number of carbon atoms of said hydrocarbon by at least 1 carbon atom.

An object of this invention is the demethylation of a saturated hydrocarbon having at least 5 carbon atoms per molecule to produce therefrom a hydrocarbon of lower molecular weight.

Another object of this invention is the demethylation of a paraffinic hydrocarbon containing at least 5 carbon atoms per molecule to produce therefrom a paraffinic hydrocarbon of lower molecular weight.

A further object of this invention is the demethylation of a saturated hydrocarbon having at least 8 carbon atoms per molecule to produce therefrom a hydrocarbon of lower molecular weight.

A still further object of this invention is the treatment of a cycloparaffinic hydrocarbon having at least 8 carbon atoms per molecule comprising a ring of 6 carbon atoms and an alkyl side chain of at least 2 carbon atoms to decrease the number of carbon atoms in said alkyl side chain of said hydrocarbon by at least 1 carbon atom by removing only one methyl group from said alkyl side chain, while retaining a portion of said side chain in chemical combination with said ring.

One specific embodiment of the present invention comprises a process for reacting hydrogen with a saturated hydrocarbon containing more than 4 carbon atoms per molecule in the presence of a hydrogenation catalyst comprising a metal selected from the group consisting of nickel and cobalt to form a hydrocarbon of lower molecular weight.

A further embodiment of the present invention comprises a process for reacting hydrogen with a paraffinic hydrocarbon containing more than 4 carbon atoms per molecule in the presence of a catalyst comprising a metal selected from the group consisting of nickel and cobalt to form a hydrocarbon of lower molecular weight.

2

Another embodiment of the present invention comprises a process for reacting hydrogen with a saturated hydrocarbon containing more than 4 carbon atoms per molecule including an alkyl group of at least 2 carbon atoms in the presence of a catalyst comprising a metal selected from the group consisting of nickel and cobalt previously reduced at a temperature of from about 425° to about 650° C.

Heretofore destructive hydrogenation methods have been utilized to produce gasoline from higher boiling oils in the presence of various hydrogenating catalysts. Such methods may be regarded as involving essentially the cracking of the higher boiling oils accompanied by hydrogenation of the products of lower molecular weight to form substantially saturated hydrocarbons boiling within the range of gasoline. The present process differs from the destructive hydrogenation treatments of the prior art, particularly in that it specifically involves the demethylation of a hydrocarbon charging stock under definite and specific conditions of operation necessary to effect a high degree of selective demethylation with substantially no accompanying undesired cracking reactions. The present process is a method for converting a saturated hydrocarbon into saturated hydrocarbons of lower molecular weights and desired structures.

By the term "selective demethylation" we mean the herein-described reaction of a saturated hydrocarbon with hydrogen in the presence of a particular catalyst whereby certain methyl groups are removed in preference to other groups from a hydrocarbon being subjected to said treatment. For example, the paraffinic hydrocarbon, 2,2,3-trimethylpentane, which has the formula:

has 5 methyl groups, 3 of which groups are combined with the quaternary carbon atom, 1 is bound to the tertiary carbon atom, this tertiary atom being adjacent to the quaternary carbon atom, and the fifth methyl group is the terminal portion of the ethyl group of the 2,2,3-trimethylpentane molecule. The terminal methyl group is combined with the secondary carbon atom of the 2,2,3-trimethylpentane molecule. Accordingly, if any one of the methyl groups attached to the quaternary carbon atom would be removed therefrom by reaction with hydrogen, the products 2,3-dimethylpentane and methane would be formed; whereas the similar splitting of the methyl group from the tertiary carbon atom would result in the formation of 2,2-dimethylpentane and methane. If the fifth methyl group, namely, that which is a part of the ethyl group of the molecule, is removed therefrom, the resultant reaction mixture would contain triptane

and methane. Accordingly, if all of the bonds between the different carbon atoms of 2,2,3-trimethylpentane are of equal strength, the probability of forming a dimethylpentane is 4 times that of forming triptane. However, we have found by experimental evidence that the bond between the quaternary and the tertiary carbon atoms is stronger than is the bond between the triptyl group and the terminal methyl group of 2,2,3-trimethylpentane. The experiments gave relatively high yields of triptane but a relatively small yield of dimethylpentanes.

We have found that different hydrocarbons which do not contain quaternary carbon atoms may also be demethylated selectively. Thus isopentane was demethylated to relatively high yields of isobutane with relatively low formation of normal pentane. The demethylation of n-hexadecane (also known as cetane) which contains only primary and secondary carbon atoms gave a reaction product containing substantial amounts of pentadecane, tetradecane, tridecane, dodecane, etc. We observed that a methyl group that is bound to a secondary carbon atom of a paraffinic hydrocarbon is the easiest to remove by demethylation, that a methyl group bound to a tertiary carbon atom is less easy to remove, and that a methyl group combined chemically with a quaternary carbon atom is the most difficult type of methyl group to split off in the form of methane. By way of explanation, a secondary carbon atom is a carbon atom that is combined with 2 other carbon atoms, a tertiary carbon atom is combined with 3 carbon atoms, and a quaternary carbon atom is combined with 4 carbon atoms.

Saturated hydrocarbons which are demethylated by the process of this invention have more than 4 carbon atoms per molecule including an alkyl group containing at least 2 carbon atoms and comprise paraffinic hydrocarbons and cycloparaffinic hydrocarbons, the latter having alkyl groups containing at least 2 carbon atoms. The paraffinic hydrocarbons include both normal and branched chain paraffins, while the cycloparaffinic or naphthenic hydrocarbons include particularly ethyl cyclohexane and other alkyl cyclohexanes of higher molecular weight containing at least one alkyl group of 2 or more carbon atoms.

The paraffinic hydrocarbons treated by the process of this invention comprise the normally liquid paraffins and particularly those containing at least 6 carbon atoms per molecule. The process is applicable to both normal and branched chain paraffinic hydrocarbons. When producing triptane, the octane, 2,2,3-trimethylpentane, mentioned above, is a preferred charging stock but this octane is not the only aliphatic hydrocarbon convertible into triptane by our process. Similarly, 2,3,3-trimethylpentane may also be demethylated into triptane, as is also true with certain highly branched nonanes, decanes, and other hydrocarbons containing a triptyl group. By a triptyl group we mean an alkyl group containing a quaternary carbon atom adjacent to a tertiary carbon atom. Thus, a triptyl group contains vicinal tertiary and quaternary carbon atoms.

The chain structures of paraffinic hydrocarbons containing a triptyl group and convertible into triptane by demethylation may be indicated by the following formula in which R¹ to R⁶ represent alkyl groups or hydrogen atoms, but with

at least one of the R¹ to R⁶ groups being an alkyl group.

If the hydrocarbon represented by the above structural formula contains a total of n carbon atoms in the groups R¹ to R⁶, inclusive, the demethylation to triptane may be represented by the equation:

Also, demethylation of a cycloparaffinic hydrocarbon having an alkyl group of at least 2 carbon atoms per molecule is illustrated by the following equations showing the demethylation of tertiary butyl-, propyl-, and ethyl-cyclohexanes.

Catalysts which we prefer for our demethylation process contain at least one of the metals selected from the group consisting of nickel and cobalt. These metals have atomic weights of from about 53 to about 60 and are also active hydrogenating catalysts. Different hydrogenation catalysts comprising these metals or their oxides are utilizable in our process, but they are preferably supported by carriers such as alumina, silica, diatomaceous earth, crushed porcelain, or some other refractory material which has substantially no adverse influence upon the demethylation reaction.

A highly active nickel catalyst which we have used in carrying out our process contained approximately 66% by weight of total nickel, 30% of diatomaceous earth, and 4% of oxygen, the latter present in nickel oxide. This catalyst was made by the general steps of suspending diatomaceous earth, also known as kieselguhr, in a dilute aqueous solution of nickel sulfate and then gradually adding thereto an excess of a hot saturated solution of sodium carbonate in water. The mixture of nickel sulfate solution and diatomaceous earth was agitated vigorously while the sodium carbonate solution was introduced thereto to form a precipitate which was removed by filtration, and was then washed with water, dried, heated, and reduced with hydrogen.

The resultant nickel-diatomaceous earth catalyst is employed in powdered form when demethylation is effected in batch type treatment or in the fluidized or fluidized fixed bed type of operation. When pelleted or formed catalyst particles are desired, the powdered mixture, preferably before being subjected to reduction with hydrogen or a reducing gas mixture, is mixed with graphite or some other lubricant and formed into pellets by a pilling machine. Other nickel-containing catalysts which may be employed similarly may be prepared to contain proportions of nickel different from those aforementioned.

Cobalt catalysts have also been prepared by essentially the same series of steps as were used in producing nickel-diatomaceous earth catalyst composites. Diatomaceous earth and cobalt nitrate so proportioned as to give essentially the

same ratio of cobalt to silica as of nickel to silica in the above-described catalyst, were mixed with water and then treated with an excess of a hot saturated solution of sodium carbonate in water. The mixture of cobalt nitrate solution and diatomaceous earth suspended therein was agitated vigorously while the sodium carbonate solution was added thereto to form a precipitate which was removed by filtration and was then washed with water, dried, and reduced to give an active cobalt-diatomaceous earth catalyst, utilizable in the form of powder or pellets in essentially the same manner as the nickel-diatomaceous earth catalyst.

Accurate control of the demethylation temperature is sometimes difficult because of the exothermic nature of the reaction. Calculations show that when one methyl group is removed as methane from one gram mole of hydrocarbon, approximately 12,500 calories of heat are evolved. Since in the hydrogenation of an olefin, the evolution of about 16,900 calories accompanies the hydrogenation of one double bond per mole of hydrocarbon, it is evident that the removal of one methyl group per mole causes the evolution of approximately 75% as much heat of reaction as does the hydrogenation of a mono-olefin. However, if the demethylation reaction is permitted to proceed further until methane is the only product, the heat of reaction becomes $12,500(n-1)$ calories, where n is the number of carbon atoms in each molecule of the original hydrocarbon charged. Thus if an octane is demethylated completely to methane, the heat of reaction is approximately 87,500 calories per mole. This heat of reaction is approximately 5.2 times the heat evolved upon hydrogenation of octene to octane. Therefore, it is apparent that if the catalyst used in demethylation, for example, of octane, is of such an active nature that excessive conversion or complete conversion to methane takes place readily, the catalyst will undergo a very rapid and excessive rise in temperature. As a result of such a high temperature, the catalyst will undergo a loss in demethylating activity. However, if the catalyst is of a less active nature, the demethylation reaction can be controlled and substantially stopped after only one or two methyl groups have been removed from the hydrocarbon charged to the process. In this case the heat of reduction is sufficiently low that it can be dissipated from the reaction zone fast enough so as to maintain a desired catalyst temperature, and so that relatively high conversions to lower molecular weight hydrocarbons can be attained.

We found that it was preferable to reduce nickel and cobalt catalysts at a temperature of from about 425° to about 650° C. rather than at a lower temperature in order to obtain a demethylation catalyst of such activity that the demethylation reaction could be controlled readily to produce demethylated hydrocarbons containing at least 4 carbon atoms per molecule. After reduction of the catalyst mixture with hydrogen at a temperature of from about 425° to about 650° C., the catalyst was of such activity that the demethylation reaction carried out in its presence could be controlled readily at relatively high conversions per pass, although we prefer to operate at such conditions as to obtain from about 20 to about 50% conversion per pass. If the catalyst was reduced only at a temperature below about 425° C., its initial activity was often so high that the exothermic heat arising from demethylation caused an excessive temperature which not

only had a tendency to spoil the activity of the catalyst, but to cause momentary, excessive conversion of the charged hydrocarbon into methane and to generate a high exothermic heat of reaction, that is, to cause the so-called "burning" of the catalyst. However, when the activity of the catalyst was modified by the reduction at a temperature of from about 425° to about 650° C., the demethylation reaction could be controlled and could be substantially stopped after only one or two methyl groups had been removed from the hydrocarbon charged to the process. Under these circumstances the heat of reaction was sufficiently low that it could be dissipated from the reaction zone rapidly enough to maintain a desired catalyst temperature so that relatively high conversions to lower molecular weight hydrocarbons could be attained and so that these conversions could be maintained for relatively long periods of time.

This demethylation process may be carried out using either batch or continuous types of operation. In batch operation, the charged hydrocarbon, hydrogen-containing gas, and catalyst are heated together in an autoclave for a time sufficient to effect demethylation. In the continuous type of treatment, which we prefer, a hydrocarbon and a hydrogen-containing gas are passed through a reactor containing a nickel, cobalt, or nickel and cobalt catalyst and the reaction products are discharged continuously from the reactor at substantially the same rate as that at which the reactants are charged thereto. The products of the demethylation treatment are fractionated by suitable means to separate the desired lower boiling hydrocarbons from the unconverted portion of the hydrocarbon material charged to the process, and said unconverted material is recycled to commingle with the hydrocarbon material charged.

The partial pressure of hydrogen in the reaction zone is an important controlling factor in the demethylation of a saturated hydrocarbon. Experimental results show that a lowering of the hydrogen partial pressure generally necessitates a lowering in the catalyst temperature in order to obtain a particular once-through yield of a desired reaction product such as triptane. However, as the demethylation reaction proceeds in the reaction zone, the partial pressure of hydrogen decreases whereas the partial pressure of methane increases. If the temperature of the catalyst layer or bed is kept constant throughout, the rate of demethylation increases as the reactants proceed through the catalyst because of the fact that the partial pressure of hydrogen is decreasing continuously and the temperature range required for high conversion is accordingly shifted toward lower temperatures. In order to have better control over the demethylation reaction, it is sometimes advantageous to charge with the saturated hydrocarbon a mixture of hydrogen and methane rather than substantially pure hydrogen. When operating in this manner, a portion of the effluent hydrogen-methane mixture is recycled to the process and commingled with the saturated hydrocarbon fraction and hydrogen-containing gas charged thereto. Since methane is more soluble in the liquid hydrocarbon product than is hydrogen, the liquid product can be subjected to a depressuring operation in a number of stages and methane is recovered from the last stage or stages. Hydrogen mixed with small amounts of methane is recovered from the 76 first depressuring stage or stages and is suitable

for recycling to the process. The removal of some of the methane by such a method prevents an excessive accumulation of methane in the recycle gas. Proper control of the demethylation reaction temperature, that is, of the catalyst temperature, is necessary since otherwise the desired products undergo further demethylation to produce saturated hydrocarbons of still lower molecular weights, the ultimate product being methane.

It is apparent from this discussion that successful demethylation requires a careful correlation of operating conditions including temperature, and hydrogen partial pressure in order to effect the selective removal of at least one methyl group as the principal reaction of the process. Accordingly, selective demethylation is in contrast with the uncontrolled destructive action whereby the hydrocarbons undergoing reaction are converted almost entirely into methane or, on the other hand, with conventional destructive hydrogenation processes wherein heavy hydrocarbons are split into lower boiling fragments which hydrogenate to form two or more molecules of liquid hydrocarbons.

The process of our invention is carried out by contacting hydrogen or a gas containing a major proportion of hydrogen and a saturated hydrocarbon having more than 4 carbon atoms per molecule with a nickel and/or cobalt catalyst at carefully correlated conditions of temperature and pressure. The catalyst temperatures utilizable in the process are from about 150° to about 385° C. Although the hydrogen partial pressure is preferably above about 3.45 atmospheres absolute, lower pressures may also be employed. Total pressures used in our process are generally not higher than about 200 atmospheres. In the presence of a catalyst containing nickel and/or cobalt, our demethylation process is carried out preferably at a catalyst temperature of from about 230° to about 350° C.

We have found that the catalyst temperature needed to obtain conversions of up to about 70% by weight of the charged saturated hydrocarbon per pass can be correlated with the hydrogen partial pressure, space velocity, and conversion by plotting against temperature the logarithm of one variable at constant values of the other two variables. The relationship which we have found may be expressed by the equation:

$$T = 0.26[T_{CR} - 100] + kD$$

where T is the catalyst temperature in °C., T_{CR} is the catalyst reduction temperature in °C., k is a factor with a range as indicated hereinafter, and D is expressed by the equation:

$$D = \log_{10}[(14.7P)^{2.98}(SV)^{1.34}C]$$

In the above equation, P represents the "initial" absolute partial pressure of hydrogen in atmospheres, SV is the hourly liquid space velocity of hydrocarbons charged to the process (expressed as liquid volume of hydrocarbons per hour per unit volume of catalyst space), and C is the conversion of the charged hydrocarbons into lower boiling hydrocarbons in per cent by volume. By the expression, the "initial" partial pressure of hydrogen, we mean the partial pressure of hydrogen in the total fluids entering the reaction zone.

The two equations referred to above may be combined as follows to express the catalyst temperature necessary for demethylation:

$$T = 0.26[T_{CR} - 100] + k \log_{10}[(14.7P)^{2.98}(SV)^{1.34}C]$$

where

T =catalyst temperature in °C.;

T_{CR} =a temperature of from 425° to 650° C. at which the catalyst was previously reduced;

k =18.4 to 23.3 at an initial absolute partial pressure of hydrogen above 3.45 atmospheres;

k =25 to 30.7 at an initial absolute partial pressure of hydrogen below 3.45 atmospheres;

P =the initial absolute partial pressure of hydrogen in atmospheres;

(SV) =the hourly liquid space velocity at which the saturated hydrocarbon is charged to contact with the catalyst;

C =the conversion of the charged saturated hydrocarbon into lower boiling saturated hydrocarbons expressed as per cent by volume of the charged hydrocarbon.

The k of the above indicated equation was evaluated upon the basis of a large number of experimental results obtained with different nickel and cobalt catalysts which had been reduced in hydrogen at several different temperatures from about 425° to about 650° C. Some of these results so obtained at widely different experimental conditions are shown in Example I. An average of about 20.7 was obtained as the value of k at absolute partial pressures of hydrogen above 3.45 atmospheres when using hydrogen or a mixture of hydrogen and methane as the processing gas, while at absolute partial pressures of hydrogen below 3.45 atmospheres, k had an average value of about 27.9. The catalyst temperature calculated by the above equation and by using the average value of k may not be the optimum temperature for obtaining a particular conversion, but it will be an operative temperature to give the desired demethylation reaction. After this operative temperature is found, it may be necessary to make slight adjustments therein in order to determine the temperature needed for optimum conversion into demethylated hydrocarbons.

The following examples are given to illustrate the process of this invention, although with no intention of limiting unduly its generally broad scope.

EXAMPLE I

A nickel-diatomaceous earth catalyst prepared as hereinabove set forth was heated in a stream of hydrogen at the temperatures indicated in Table I for 12 hours and then cooled to room temperature, after which a mixture of nitrogen and air was passed through the reduced catalyst to render it substantially non-pyrolytic. The resultant catalyst was then used as a granular filler in a steel reactor through which hydrogen and a trimethylpentane mixture, the latter consisting of approximately 35% of 2,2,3-trimethylpentane, 10% of 2,3,3-trimethylpentane, and 55% of 2,3,4-trimethylpentane, were passed at total absolute pressures of from about 4.4 to about 55.5 atmospheres corresponding to partial hydrogen pressures of from about 3.4 to about 44.4 atmospheres. Results obtained in these runs are shown in Table I together with the value of k calculated from the experimentally determined conversions to lower hydrocarbons observed at the indicated catalyst temperatures, pressures and space velocities.

The converted material consisted of 2,3-dimethylpentane and triptane as the major products with minor amounts of 2,2-dimethylpentane, neohexane, and 2,3-dimethylbutane.

EXAMPLE II

A cobalt-diatomaceous earth catalyst was prepared in the same manner as was the nickel-diatomaceous earth catalyst described in Example I with the exception that the cobalt carbonate was decomposed by heating before being formed into pellets. The pelleted cobalt-diatomaceous earth catalyst was reduced by heating in hydrogen at 371° C. for 16 hours and then by continuing the heating in hydrogen at 454° C. for 24 hours. The catalyst was then cooled to about 20° C. and used as a filler in a reactor through which 4.8 molecular proportions of hydrogen and 1 molecular proportion of trimethylpentane were passed at the conditions shown in Table II. In each of these runs the trimethylpentane mixture was charged at an hourly liquid space velocity of 2.0.

The demethylation products obtained in run Nos. 13 and 14 were similar to those obtained in Example I. The above indicated run Nos. 15-17 yielded neopentane as the main reaction product.

The nature of the present invention and type of results obtained are evident from the specification and examples although neither section should be construed to limit unduly the broad scope of the invention.

We claim as our invention:

1. A process for demethylating a paraffinic hydrocarbon having at least 5 carbon atoms per molecule to produce therefrom a paraffinic hydrocarbon of lower molecular weight which comprises reacting a paraffinic hydrocarbon having at least 5 carbon atoms per molecule including an alkyl group of at least 2 carbon atoms with hydrogen in the presence of a catalyst comprising a metal selected from the group consisting of nickel and cobalt at a catalyst temperature of from about 150° C. to about 385° C. and defined by the equation:

$$T=0.26[T_{CR}-100]+k \log_{10}[(14.7 P)^{2.98}(SV)^{1.34} C]$$

where

T=catalyst temperature in °C.;

T_{CR}=a temperature of from 425° to 650° C. at which the catalyst was previously reduced;

k=18.4 to 23.3 at an initial absolute partial pressure of hydrogen above 3.45 atmospheres;

P=the initial absolute partial pressure of hydro-

gen in atmospheres;

5 (SV)=the hourly liquid space velocity at which the paraffinic hydrocarbon is charged to contact with the catalyst;

C=the conversion of the charged paraffinic hydrocarbon into lower boiling saturated hydrocarbons expressed as per cent by volume of the charged hydrocarbon.

10 2. A process for demethylating neohexane to produce therefrom neopentane which comprises reacting neohexane with hydrogen in the presence of a catalyst comprising a metal selected from the group consisting of nickel and cobalt at a catalyst temperature of from about 150° C. to about 385° C. and defined by the equation:

$$T=0.26[T_{CR}-100]+k \log_{10}[(14.7 P)^{2.98}(SV)^{1.34} C]$$

20 where

T=catalyst temperature in °C.;

T_{CR}=a temperature of from 425° to 650° C. at which the catalyst was previously reduced;

25 k=18.4 to 23.3 at an initial absolute partial pressure of hydrogen above 3.45 atmospheres;

k=25 to 30.7 at an initial absolute partial pressure of hydrogen below 3.45 atmospheres;

P=the initial absolute partial pressure of hydro-

30 gen in atmospheres;

(SV)=the hourly liquid space velocity at which the neohexane is charged to contact with the catalyst; and

C=the conversion of the charged neohexane into neopentane expressed as per cent by volume of the charged neohexane.

35 3. A process for demethylating a paraffinic hydrocarbon having at least 8 carbon atoms per molecule to produce therefrom a paraffinic hydrocarbon having 1 carbon atom less per molecule which comprises reacting a paraffinic hydrocarbon having at least 8 carbon atoms per molecule including in each molecule an alkyl group of at least 2 carbon atoms with hydrogen in the presence of a catalyst comprising a metal selected from the group consisting of nickel and cobalt at a catalyst temperature of from about 150° C. to about 385° C. and defined by the equation:

$$T=0.26[T_{CR}-100]+k \log_{10}[(14.7 P)^{2.98}(SV)^{1.34} C]$$

40 where

T=catalyst temperature in °C.;

T_{CR}=a temperature of from 425° to 650° C. at which the catalyst was previously reduced;

45 k=18.4 to 23.3 at an initial absolute partial pressure of hydrogen above 3.45 atmospheres;

k=25 to 30.7 at an initial absolute partial pressure of hydrogen below 3.45 atmospheres;

P=the initial absolute partial pressure of hydro-

50 gen in atmospheres;

(SV)=the hourly liquid space velocity at which the paraffinic hydrocarbon is charged to contact with the catalyst;

C=the conversion of the charged paraffinic hydrocarbon into lower boiling paraffinic hydrocarbons expressed as per cent by volume of the charged hydrocarbon;

55 and thereafter separating demethylated paraffinic hydrocarbons formed in the process from unconverted paraffinic hydrocarbon and recycling said unconverted paraffinic hydrocarbon to further treatment with hydrogen in the presence of the catalyst.

60 4. A process for demethylating a cycloparaffinic

hydrocarbon having at least 8 carbon atoms per molecule to produce therefrom a cycloparaffinic hydrocarbon of lower molecular weight which comprises reacting a cycloparaffinic hydrocarbon having at least 8 carbon atoms per molecule including in each molecule an alkyl group of at least 2 carbon atoms with hydrogen in the presence of a catalyst comprising a metal selected from the group consisting of nickel and cobalt at a temperature of from about 150° C. to about 385° C. and defined by the equation:

$$T=0.26[T_{CR}-100]+k \log_{10}[(14.7 P)^{2.98}(SV)^{1.34} C]$$

where

T=catalyst temperature in °C.;

T_{CR}=a temperature of from 425° to 650° C. at which the catalyst was previously reduced;

k=18.4 to 23.3 at an initial absolute partial pressure of hydrogen above 3.45 atmospheres;

k=25 to 30.7 at an initial absolute partial pressure of hydrogen below 3.45 atmospheres;

P=the initial absolute partial pressure of hydrogen in atmospheres;

(SV)=the hourly liquid space velocity at which the cycloparaffinic hydrocarbon is charged to contact with the catalyst;

C=the conversion of the charged cycloparaffinic hydrocarbon into lower boiling saturated hydrocarbons expressed as per cent by volume of the charged hydrocarbon.

5. A process for producing triptane which comprises reacting a paraffinic hydrocarbon having at least 8 carbon atoms per molecule including a triptyl group with hydrogen in the presence of a catalyst comprising a metal selected from the group consisting of nickel and cobalt at a catalyst temperature of from about 150° C. to about 385° C. and defined by the equation:

$$T=0.26[T_{CR}-100]+k \log_{10}[(14.7 P)^{2.98}(SV)^{1.34} C]$$

where

T=catalyst temperature in °C.;

T_{CR}=a temperature of from 425° to 650° C. at which the catalyst was previously reduced;

k=18.4 to 23.3 at an initial absolute partial pressure of hydrogen above 3.45 atmospheres;

k=25 to 30.7 at an initial absolute partial pressure of hydrogen below 3.45 atmospheres;

P=the initial absolute partial pressure of hydrogen in atmospheres;

(SV)=the hourly liquid space velocity at which the paraffinic hydrocarbon is charged to contact with the catalyst.

C=the conversion of the charged paraffinic hydrocarbon into lower boiling paraffinic hydrocarbons expressed as per cent by volume of the charged hydrocarbon.

6. A process for producing triptane which comprises reacting hydrogen and a paraffinic hydrocarbon with a structure indicated by the formula:

in which R¹ represents an alkyl group and R² to R⁶, inclusive, represent at least one member of the class consisting of an alkyl group and a hydrogen atom, the process being carried out in the presence of a catalyst comprising a metal selected from the group consisting of nickel and cobalt and at a catalyst temperature of from about

150° C. to about 385° C. and defined by the equation:

$$T=0.26[T_{CR}-100]+k \log_{10}[(14.7 P)^{2.98}(SV)^{1.34} C]$$

where

T=catalyst temperature in °C.;

T_{CR}=a temperature of from 425° to 650° C. at which the catalyst was previously reduced;

k=18.4 to 23.3 at an initial absolute partial pressure of hydrogen above 3.45 atmospheres;

k=25 to 30.7 at an initial absolute partial pressure of hydrogen below 3.45 atmospheres;

P=the initial absolute partial pressure of hydrogen in atmospheres;

15 (SV)=the hourly liquid space velocity at which the paraffinic hydrocarbon is charged to contact with the catalyst.

C=the conversion of the charged paraffinic hydrocarbon into lower boiling saturated hydrocarbons expressed as per cent by volume of the charged hydrocarbon.

7. A process for demethylating a saturated hydrocarbon to produce therefrom a saturated hydrocarbon of lower molecular weight which comprises reacting a saturated hydrocarbon having at least 5 carbon atoms per molecule including an alkyl group of at least 2 carbon atoms with hydrogen in the presence of a catalyst comprising

25 a metal selected from the group consisting of nickel and cobalt at a catalyst temperature of from about 150° C. to about 385° C. and defined by the equation:

$$T=0.26[T_{CR}-100]+k \log_{10}[(14.7 P)^{2.98}(SV)^{1.34} C]$$

where

T=catalyst temperature in °C.;

T_{CR}=a temperature of from 425° to 650° C. at which the catalyst was previously reduced;

40 k=18.4 to 23.3 at an initial absolute partial pressure of hydrogen above 3.45 atmospheres;

k=25 to 30.7 at an initial absolute partial pressure of hydrogen below 3.45 atmospheres;

P=the initial absolute partial pressure of hydrogen in atmospheres;

(SV)=the hourly liquid space velocity at which the saturated hydrocarbon is charged to contact with the catalyst; and

45 C=the conversion of the charged saturated hydrocarbon into lower boiling saturated hydrocarbons expressed as per cent by volume of the charged hydrocarbon.

8. A process for demethylating a paraffinic hydrocarbon having at least 5 carbon atoms per molecule to produce therefrom a paraffinic hydrocarbon of lower molecular weight which comprises reacting said paraffinic hydrocarbon having at least 5 carbon atoms per molecule with hydrogen in the presence of a catalyst comprising

55 a metal selected from the group consisting of nickel and cobalt at a catalyst temperature of from about 150° C. to about 385° C. and defined by the equation:

$$T=0.26[T_{CR}-100]+k \log_{10}[(14.7 P)^{2.98}(SV)^{1.34} C]$$

where

T=catalyst temperature in °C.;

T_{CR}=a temperature from 425° to 650° C. at which the catalyst was previously reduced;

k=1.4 to 23.3 at an initial absolute partial pressure of hydrogen above 3.45 atmospheres;

k=25 to 30.7 at an initial absolute partial pressure of hydrogen below 3.45 atmospheres;

75

P=the initial absolute partial pressure of hydrogen in atmospheres;

(SV)=the hourly liquid space velocity at which the paraffinic hydrocarbon is charged to contact with the catalyst; and

C=the conversion of the charged paraffinic hydrocarbon into lower boiling paraffinic hydrocarbons expressed as per cent by volume of the charged hydrocarbon.

9. A process for demethylating a saturated hydrocarbon having at least 8 carbon atoms per molecule to produce therefrom a saturated hydrocarbon of lower molecular weight which comprises reacting a saturated hydrocarbon having at least 8 carbon atoms per molecule including in each molecule an alkyl group of at least 2 carbon atoms with hydrogen in the presence of a catalyst comprising a metal selected from the group consisting of nickel and cobalt at a catalyst temperature of from about 150° C. to about 385° C. and defined by the equation:

$$T=0.26[T_{CR}-100]+k \log_{10}[(14.7P)^{2.98}(SV)^{1.34}C]$$

where

T=catalyst temperature in ° C.;

T_{CR}=a temperature of from 425° to 650° C. at which the catalyst was previously reduced;

k=18.4 to 23.3 at an initial absolute partial pressure of hydrogen above 3.45 atmospheres;

k=25 to 30.7 at an initial absolute partial pressure of hydrogen below 3.45 atmospheres;

P=the initial absolute partial pressure of hydrogen in atmospheres;

(SV)=the hourly liquid space velocity at which the saturated hydrocarbon is charged to contact with the catalyst; and

C=the conversion of the charged saturated hydrocarbon into lower boiling saturated hydrocarbons expressed as per cent by volume of the charged hydrocarbon.

10. A process for demethylating a cycloparaffinic hydrocarbon having at least 8 carbon atoms per molecule to produce therefrom a saturated hydrocarbon having 1 carbon atom less per molecule which comprises reacting a cycloparaffinic hydrocarbon having at least 8 carbon atoms per

molecule including in each molecule a ring of 6 carbon atoms and an alkyl group of at least 2 carbon atoms with hydrogen in the presence of a catalyst comprising a metal selected from the group consisting of nickel and cobalt at a catalyst temperature of from about 150° to about 385° C. and defined by the equation:

$$T=0.26[T_{CR}-100]+k \log_{10}[(14.7P)^{2.98}(SV)^{1.34}C]$$

where

T=catalyst temperature in ° C.;

T_{CR}=a temperature of from 425° to 650° C. at which the catalyst was previously reduced;

k=18.4 to 23.3 at an initial absolute partial pressure of hydrogen above 3.45 atmospheres;

k=25 to 30.7 at an initial absolute partial pressure of hydrogen below 3.45 atmospheres;

P=the initial absolute partial pressure of hydrogen in atmospheres;

20 (SV)=the hourly liquid space velocity at which the cycloparaffinic hydrocarbon is charged to contact with the catalyst; and

C=the conversion of the charged cycloparaffinic hydrocarbon into lower boiling saturated hydrocarbons expressed as per cent by volume of the charged hydrocarbon.
